UNITED STATES PATENT OFFICE.

JANE A. MOREHOUSE, OF NEWARK, NEW JERSEY.

BABY-JUMPER.

SPECIFICATION forming part of Letters Patent No. 777,386, dated December 13, 1904.

Application filed April 30, 1904. Serial No. 205,711. (No model.)

To all whom it may concern:

Be it known that I, JANE A. MOREHOUSE, a citizen of the United States, and a resident of Newark, in the county of Essex and State of New Jersey, have invented a new and Improved Baby-Jumper, of which the following is a full, clear, and exact description.

The purpose of the invention is to provide a spring-supported rest or seat for young children, so constructed and suspended that a saddle is formed beneath an opening in the frame, which saddle is connected with said frame at the front and rear of the opening and is fitted with an upholstered or padded seat so shaped at its side edges as to afford perfect freedom to the lower limbs of the child when seated and to so sustain the frame from an overhead support that a spring-controlled action will be obtained in a vertical direction while the frame is free to swing laterally.

Another purpose of the invention is to provide a table or tray adapted to hold food or playthings, which tray is removably connected with the frame of the jumper.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved baby-jumper. Fig. 2 is a plan view of the same. Fig. 3 is a central section taken practically on the line 3 3 of Fig. 2, and Fig. 4 is an enlarged detail sectional view illustrative of the manner in which the table or tray is connected with the body-frame.

A represents what I term the "body-frame," and this body-frame may be made in one piece or in sections. It is adapted to be horizontally held, being provided at its central portion with a preferably circular opening 10 of sufficient size to accommodate the lower portion of the trunk of the average child.

The body-frame A is held in the horizontal position above referred to preferably by means of four cords 11, which are usually passed through openings at the corner por-

tions of the frame and are then knotted beneath the frame, as is shown at 11^a in Fig. 3; but these cords may be secured to the frame A in any suitable or approved manner.

The cords are brought together at their upper ends and are preferably secured to the lower portion of a spring 12, which spring in its turn is attached to an overhead support; but the cords 11 when together may be attached directly to a rigid overhead support, if so desired. 55

A saddle B is suspended from the body-frame A. This saddle is made preferably of a pliable material—such as leather, oil-cloth, leatherette, or the like—and comprises a rear 65 apron-section 13, a forward apron-section 14, and a connecting seat-section 15.

The upper ends of the forward and rear apron-sections are secured in any suitable or approved manner to the body-frame at corresponding portions of the opening 10 therein. Preferably the rear apron-section 13 is wider than the forward apron-section 14. 70

The seat-section 15 is upholstered—that is to say, it is of pillow formation, having a filling 16 of a soft material, as is shown best in Fig. 3—and the side edges of the seat-section 15 are oppositely curved, as is shown in Fig. 2, so that the seat-section will accommodate a child, the lower limbs passing down, one at 80 each side of the said seat-section, without the possibility of chafing or irritating the person, and the upholstering in the seat-section 15 renders this portion exceedingly comfortable when in use. 85

The frame A may be a board or it may be made of any suitable material and may be, and usually is, provided with a covering 17 of some description. In order that the edge of the opening 10 in the body-frame shall not bear 90 unpleasantly upon the body of the occupant of the jumper, the said edge of the said opening is provided with a padding 17^a of any suitable or approved construction, as is illustrated in Fig. 3. 95

While the device is practically complete as above described, a table or tray 18 is usually employed in connection therewith at the front, and on this table or tray food may be placed, toys, or any other desired article. This table 100

or tray 18 is provided with angular brackets 19, the outer vertical and downwardly-extending members 20 of said brackets being made to enter slots or openings 21, produced in the 5 body-frame A, as is shown best in Fig. 4.

Having thus described my invention, I claim as new and desire to secure by Letters Patent—

1. In a baby-jumper, a body-frame having an opening therein adapted to accommodate 10 the lower portion of the trunk of the occupant, a saddle adapted to be suspended from the under portion of the body-frame below the opening in said frame, which saddle consists of front and rear vertically-extending 15 apron-sections and a lower connecting seat-section, padded and having its side edges oppositely curved, as described.

2. A baby-jumper consisting of a body-frame having an opening therein, a padding 20 at the edge of the opening, suspension-cords

attached to the body-frame, a spring connected with said cords at their upper ends, a saddle extending downward from the under portion of the body-frame at the opening in the same, the said saddle consisting of upright 25 front and rear apron-sections, the rear apron-section being wider than the forward one, and a connecting seat-section, upholstered and provided with side edges curved in opposite directions, a table, and brackets carried by 30 the said table, the body-frame being provided with openings in which members of the said brackets are removably entered, as described.

In testimony whereof I have signed my name to this specification in the presence of two sub- 35 scribing witnesses.

JANE A. MOREHOUSE.
